UNITED STATES PATENT OFFICE.

GEORGE MILLER, OF JERSEY CITY, NEW JERSEY.

DESIGN FOR A BOTTLE.

SPECIFICATION forming part of Design No. 28,790, dated June 7, 1898.

Application filed May 9, 1898. Serial No. 680,227. Term of patent 7 years.

To all whom it may concern:

Be it known that I, GEORGE MILLER, a citizen of the United States, residing in Jersey City, in the county of Hudson and State of New Jersey, have invented and produced a new and original Design for a Bottle, of which the following is a specification, reference being had to the accompanying drawing, forming a part thereof, which represents a perspective view of a bottle embodying the features of my design.

Where the neck A of the bottle connects with the body B an annular beading *a* appears. The upper portion *b* of the body is semispherical or dome-shaped and decorated with fleur-de-lis figures. The body tapers from the dome to the bottom, where it is of greater diameter. The tapering portion of

the body is formed with longitudinal channels *b'*, whereby the body between the dome and bottom is polygonal in cross-section. The body of the bottle near the bottom is decorated with a band of individual beads.

The leading feature of the design consists in a bottle the body whereof has an upper dome-shaped portion, a base, and a tapered longitudinally-paneled section between the dome and the base.

I claim—

The design for a bottle herein shown and described.

GEORGE MILLER.
